US00D610860S

(12) **United States Design Patent**
Bodum

(10) **Patent No.:** **US D610,860 S**
(45) **Date of Patent:** **** Mar. 2, 2010**

(54) **BEVERAGE MAKER**

(75) Inventor: **Jorgen Bodum**, Meggen (CH)

(73) Assignee: **Pi-Design AG**, Triengen (CH)

(**) Term: **14 Years**

(21) Appl. No.: **29/329,204**

(22) Filed: **Dec. 10, 2008**

(30) **Foreign Application Priority Data**

Jun. 10, 2008 (WO) DM/070 278
Jun. 30, 2008 (WO) DM/070 345

(51) **LOC (9) Cl.** **07-01**

(52) **U.S. Cl.** **D7/319; D7/317**

(58) **Field of Classification Search** D7/300,
D7/316-319, 312, 322; 99/297, 287, 298,
99/279; 366/256

See application file for complete search history.
